(57) **CLAIM**

I claim the ornamental design for a hose clamp with transversely oriented tightening screw, as shown and described.

DESCRIPTION

FIG. 1 is a perspective view of a hose clamp with transversely oriented tightening screw showing my new design; FIG. 2 is a right side elevational view thereof; FIG. 3 is a left side elevational view thereof; FIG. 4 is a rear elevational view thereof; FIG. 5 is a front elevational view thereof; FIG. 6 is top plan view thereof; FIG. 7 is a bottom plan view thereof; and, FIG. 8 is a reduced perspective view showing the hose clamp with transversely oriented tightening screw in use; the broken lines depict environmental structure and form no part of the claimed design.
